CLAIM

The ornamental design for a desk storage container, as shown and described.

DESCRIPTION

FIG. 1 is a top, front and right side perspective view of the desk storage container;

FIG. 2 is a front elevational view thereof;

FIG. 3 is a rear elevational view thereof;

FIG. 4 is a left side elevational view, the right side view being a mirror image thereof;

FIG. 5 is a top plan view thereof; and,

FIG. 6 is a bottom plan view thereof.

The broken lines are for illustrative purposes only and form no part of the claimed design.
